UNITED STATES PATENT OFFICE.

RALPH FRANKLIN THACKSTON, OF ANDERSON, SOUTH CAROLINA.

BOBBIN-SUPPORTER FOR LOOMS.

1,297,420.

Specification of Letters Patent. Patented Mar. 18, 1919.

Application filed April 19, 1918. Serial No. 229,548.

To all whom it may concern:

Be it known that I, RALPH F. THACKSTON, a citizen of the United States, residing at Anderson, in the county of Anderson, 5 State of South Carolina, have invented a new and useful Bobbin-Supporter for Looms; and I do hereby declare the following to be a full, clear, and exact description of the invention, such as will enable others 10 skilled in the art to which it appertains to make and use the same.

This invention relates to an improved bobbin supporter for looms, particularly the Draper type of loom, and one of the objects 15 of the invention is to provide a device of this kind having improved simple, efficient and practical features of construction.

A further object of the invention is to provide an improved bobbin supporter and 20 means for preventing the bobbin supporter from tilting excessively, in fact to prevent the bobbin supporting end of the supporter from moving too low and hanging on the edge of the shuttle box.

25 A further object of the invention is the provision of yieldable means for the bobbin supporter, and means for adjusting and regulating the limiting of the bobbin supporter.

In practical fields the details of construction 30 may necessitate alterations falling within the scope of what is claimed.

The invention comprises further features and combination of parts as hereinafter set forth, shown in the drawings and claimed.

35 In the drawings:—

Figure 1 is a view in section through a portion of a cylinder battery of a loom preferably a Draper type of loom, showing the application of the bobbin supporter.

40 Fig. 2 is a plan view of the bobbin supporter, showing the opposite sides of the cylinder battery in section.

Fig. 3 is a perspective view of the bobbin supporter detached.

45 Fig. 4 is a sectional view through the bobbin supporter.

Fig. 5 is a sectional view through a modified form of bobbin supporter.

Referring more especially to the drawings 50 1 designates a conventional form of cylinder battery, for the reception of the bobbins 2, and 3 denotes a shuttle box, and 4 is a rocking transerrer, which is pivoted at 5. Pivoted at 6 to a projection 7 of a 55 curved flange 8 of the frame 9 of the loom is the improved bobbin supporter, which in

plan view is substantially U-shaped. This bobbin supporter 10 has its two arms substantially midway their ends provided with opposite openings 11, to receive the pivot 60 pin 6. The end portion 12 of the arm 13 of the supporter is constructed to engage the head of the bobbin. In fact the end 12 is provided with a plurality of grooves 13 to engage the usual rings 14 of the bobbin. 65 The other arm 15 of the bobbin supporter is deflected or disposed at an angle to the arm 13, and is provided with a bifurcation 16. Carried by the side of the frame 9, (which incases the battery) is a forked arm 70 17. A rod 18 is disposed between the forks and one end of this rod or bolt designated by the numeral 19 engages the bifurcation 16 of the arm 15 of the bobbin supporter, there being a nut 20 on the end of this rod 75 or bolt, whereby as the bobbin is struck by the hammer end 21 of the transerrer, the bobbin supporter is rocked upon its pivot 6, against improved tensioning means, as will appear later. When the bobbin supporter is 80 rocked, the bobbin is transferred or discharged from the battery to the shuttle box. The end 22 of the rod or bolt is provided with a head 23. A tubular casing 24 is mounted upon the rod or bolt with its 85 curved end 25 in contact with the head 23. A second tubular casing 26 telescopes into the casing 24. At the end 25 of the casing 24 a shoulder 27 is provided to limit the inwardly telescoping action of the inner 90 casing 26. The interior surface of the casing 26 is spaced from the rod or bolt 18 as shown. Mounted upon the rod or bolt are metallic washers 29 and 30, one upon each side of the forked arm 17. Also mounted 95 upon the rod or bolt adjacent the bifurcated portion of the arm 15 of the bobbin supporter is a metallic washer 31, and adjacent this washer 31 is a leather or fiber washer 32. Interposed between the leather or fiber 100 washer 32 and the washer 30 and surrounding the rod or bolt is a coil spring 33. A coil spring 34 extends telescopically into the tubular casing 26, in contact with the shoulder 35 at its interior end. The other 105 end of the coil spring 34 engages the washer 29. The casing 24 has a threaded opening 37 in its wall for the reception of a set screw or bolt 36, which engages the outer surface of the casing 26 for holding the same in different adjusted positions relative to the casing 24. It is to be seen that when the ham-

mer end of the transerrer strikes the bobbin and transfers or discharges the same from the battery, the bobbin supporter will be rocked upon its pivot. The arm 15 will then pull upon the rod or bolt, which will compress the spring 34, and the spring 33 will expand. The casings will have been adjusted as required so as to accommodate the movement of the supporter, and when 10 the spring 34 is compressed, the casing 26 will contact with the forked arm and limit the bobbin supporter in its tilting movement, and consequently prevent the bobbin supporting end of the arm 13 from moving 15 too far and preventing it from hanging on the edge of the shuttle box. It is to be noted that by adjusting the inner casing 26, the tilting action of the bobbin supporter may be varied, according to the different diameters of bobbin heads. However, when uniform bobbins are employed in connection with the loom the inner casing 26 may be either dispensed with, or its adjustment not used, and in this case the nut 20 may be adjusted to regulate the head 23 of the bolt 20 relative to the forked arm, whereby the casing 24 (in case the casing 26 or its adjustment are eliminated) may contact with the forked arm, so as to limit the supporter in 30 its proper position, in order that it will not hang on the edge of the shuttle box. In Fig. 5 a modified construction of bobbin supporter for looms is disclosed. However, in this structure the inner casing 26 is eliminated. In fact only a single casing 24 is employed, and otherwise the structure is the same as the structure shown in the other figures.

The invention having been set forth what 40 is claimed as new and useful is:—

1. The combination with a bobbin supporter, of a formed arm carried by the frame of the loom, said supporter having a pair of arms, one for supporting the bobbin, and 45 the other having a yielding connection with the forked arm, and means carried by said connection to contact with the forked arm to limit the bobbin supporting arm of the supporter in its downward movement, said 50 yielding connection comprising a rod passing through the fork of said arm, one end of the rod having a loose connection with one of the arms of the supporter, a cushioning spring between one of the arms of the 55 supporter and the forked arm, said rod having a head, a casing on the rod adjacent the

head, and a coil spring between the casing and telescoping therein and the forked arm.

2. The combination with a bobbin supporter, of a forked arm carried by the frame of the loom, said supporter having a pair of arms, one for supporting the bobbin, and the other having a yielding connection with the forked arm, and means carried by said connection to contact with the forked 60 arm to limit the bobbin supporting arm of the supporter in its downward movement, said yielding connection comprising a rod passing through the fork of said arm, one end of the rod having a loose connection 70 with one of the arms of the supporter, a cushioning spring between one of the arms of the supporter and the forked arm, said rod having a head, a casing on the rod adjacent the head, a second casing telescoping 75 the first tubular casing, means carried by the first tubular casing for holding the second in different relative adjusted positions, and a coil spring telescoping the second casing and interposed between the second cas- 80 ing and the forked arm.

3. The combination with a bobbin supporter, of a forked arm carried by the frame of the loom, said supporter having a pair of arms, one for supporting the bobbin and 85 the other being slotted, means rockably mounting the supporter on the frame of the loom, a rod loosely engaging the slot of the arm of the supporter and engaging said forked arm, means on one end of the rod to 90 hold it in engagement with the slot, the other end of the rod having a head, a pair of casings, one telescopically fitting the other and mounted on the rod adjacent the head, means carried by one of the casings 95 for holding the inner casing extended toward the forked arm, a pair of coil springs in surrounding relation to the rod, one on side of the forked arm and fitting telescopically into the inner casing, and the other on the opposite side of the forked arm, and means interposed between the last mentioned spring and the slotted arm of the 100 supporter.

In testimony whereof I have signed my 105 name to this specification in the presence of two subscribing witnesses.

RALPH FRANKLIN THACKSTON.
